CLAIM

The ornamental design for a grip diameter adapter kit, as shown and described.

DESCRIPTION

1. Grip for strength training bars
- 1.1 : Reference perspective view of the state in use (assembled)
- 1.2 : Side view (right and left)
- 1.3 : Perspective view (assembled)
- 1.4 : First part front and back view
- 1.5 : First part bottom view
- 1.6 : First part right and left view
- 1.7 : First part perspective view
- 1.8 : First part top view
- 1.9 : Second part front and back view
- 1.10 : Second part bottom view
- 1.11 : Second part right and left view
- 1.12 : Second part perspective view
- 1.13 : Second part top view
- 1.14 : Third part front and back view
- 1.15 : Third part bottom view
- 1.16 : Third part right and left view
- 1.17 : Third part perspective view
- 1.18 : Third part top view

The present design is for a grip used to increase the diameter of bar portions of barbells or dumbbells. The individual parts of the grip have front/back and left/right symmetry such that the right and left views, as well as front and back views, are identical. The front, back, top, and bottom views of the grip shown in the assembled state of use are identical to the front, back, top, and bottom views of the third part. The broken
